US0D1088302S

(12) **United States Design Patent** (10) **Patent No.:** **US D1,088,302 S**
(45) **Date of Patent:** **** Aug. 12, 2025**

(54) **LED BULB**

(71) Applicant: **Lumileds LLC**, San Jose, CA (US)

(72) Inventors: **Shengjin Chen**, Shanghai (CN);
Anderson Luo, Shanghai (CN);
Stefanie Wang, Shanghai (CN); **Irene Wen**, Shanghai (CN)

(73) Assignee: **LUMILEDS LLC**, San Jose, CA (US)

(**) Term: **15 Years**

(21) Appl. No.: **35/003,214**

(22) Filed: **Feb. 2, 2024**

(80) **Hague Agreement Data**

Int. Filing Date: **Feb. 2, 2024**

Int. Reg. No.: **DM/237822**

Int. Reg. Date: **Feb. 2, 2024**

Int. Reg. Pub. Date: **Jun. 21, 2024**

(51) **LOC (15) Cl.** **26-04**

(52) **U.S. Cl.**

USPC **D26/2**
